UNITED STATES PATENT OFFICE

CALEB S. BRAGG, OF PALM BEACH, FLORIDA, AND VICTOR W. KLIESRATH, OF PORT WASHINGTON, NEW YORK, ASSIGNORS TO BRAGG-KLIESRATH CORPORATION, OF LONG ISLAND CITY, NEW YORK, A CORPORATION OF NEW YORK

METHOD OF AND APPARATUS FOR OPERATING SUCTION-ACTUATED DEVICES IN CONNECTION WITH THE SUCTION PASSAGES OF INTERNAL-COMBUSTION ENGINES

Application filed June 16, 1925, Serial No. 37,407. Renewed July 13, 1929.

Our invention consists in the novel features hereinafter described, reference being had to the accompanying drawings, which illustrate several embodiments of the same selected by us for purposes of illustration, and the said invention is fully disclosed in the following description and claims.

In the operation of vacuum brakes or other suction actuated devices in connection with automotive vehicles, it is extremely convenient to obtain the necessary suction, or partial vacuum, from the suction passage of an internal combustion engine ordinarily employed for the propulsion of the vehicle, and preferably between the throttle valve for controlling the supply of explosive mixture, and the cylinder. To this end it is convenient and desirable to connect such suction actuated device with the intake manifold of the engine which forms part of said suction passage. It will be understood, further, that the air exhausted from the suction actuating mechanism and delivered into the intake manifold necessarily has a tendency to reduce the degree of rarification therein, and therefore to prevent the drawing in of the proper quantity of liquid fuel from the atomizer, or to dilute the explosive mixture passing through the suction passage frequently to such an extent that the resulting mixture will not readily ignite. In either case the engine, if turning over idly, would be likely to stall, and the admission of air into the manifold in this manner, would also materially delay the starting of the engine. It is also to be understood that for the proper operation of the vacuum brake mechanism of a motor vehicle, it is desirable that the air shall be withdrawn from the brake actuating mechanism as rapidly as possible, in order to insure instantaneous operation of the brake mechanism, and that if the connection between the brake actuating mechanism and the intake manifold is restricted for the purpose of avoiding the stalling of the engine and delay in starting, the result will necessarily retard the operation of the brake mechanism to a greater or less extent. It is also to be understood that in the operation of vacuum brake mechanism and other suction actuated

devices, the moving part, as the piston, is acted upon by differential pressures brought about by producing a condition of rarification on one side of the piston and admitting a higher pressure fluid, usually atmospheric air, on the other side of the piston, under the control of a suitable reversing valve mechanism, and that the air so admitted is subsequently withdrawn and delivered into the suction passage of the engine, where the suction is provided by connection between the actuator and the intake manifold.

In our former application for Letters Patent of the United States filed February 26, 1925, and given Serial No. 11,683, we have described a method of and apparatus for operating suction actuated device in connection with the suction passage of an internal combustion engine, for the purpose of preventing the objectionable features above mentioned, and the stalling of the engine if idling, or otherwise interfering with its operation, by supplying motor fuel to the air which is exhausted from the suction actuated device, before it reaches the intake manifold, so that when it does enter the manifold, it will be in the form of an explosive mixture, which will combine with the explosive charges delivered into the manifold from the carburetor, and will not have the effect of slowing down or stalling the engine.

Our present invention has for its object to provide an improved device for collecting liquid hydrocarbon or motor fuel from the mixture passing through the suction passage of the engine and holding it in a capillary retaining means, permeable by the air withdrawn from a suction operated device (as the power actuator for operating the brake mechanism of an automotive vehicle) on its way to the intake manifold so that the air withdrawn from the actuator or other suction actuated device will be forced to pass through said capillary retaining means, and in intimate contact with finely divided particles of the liquid fuel, so as to insure the proper carburetion of the air before it reaches the intake manifold. In some instances we may cause the capillary retaining means to project into the intake manifold, or into the ver-

tical passage thereto leading from the carburetor, and into the stream of air and liquid hydrocarbon vapor or mist passing therethrough to form the explosive charges of the engine, so that the said projecting portions of the capillary retaining means will collect from the mixture sufficient liquid hydrocarbon to effect the carburetion of the air withdrawn from a suction actuated device. 5 The capillary retaining means may also be supplied in part with liquid fuel from the portion thereof which condenses upon the walls of the intake manifold, or the passage from the carburetor leading thereto. In our 10 preferred construction the capillary retaining means is in the form of a coil of wicking, retained in a receptacle interposed in the suction pipe leading from the suction actuated device to the intake manifold, and portions thereof may extend upwardly into the 15 intake manifold or laterally into the vertical passage from the carburetor to the intake manifold, in which latter case the capillary retaining material is supplied from two 20 sources, and any excess of liquid accumulated by the capillary retaining material will be drained back into the passage from the carburetor to the intake manifold and restored to the current of mixture. 25

It will be understood that our invention is no part of the engine carburetor, which supplies the charges to the engine at all speeds and is responsive to engine conditions, but on the contrary is entirely independent of the 30 engine carburetor, and it is operative only in conjunction with an intermittently operated suction actuated device, connected with the suction passage of the engine, to permit the intermittent operation of the suction actuated device without materially diluting the 35 explosive mixture to interfere with the normal operation of the engine under the control of the throttling valve or the stalling of the engine when idling. 40

In the accompanying drawings, 45

Fig. 1 is a diagrammatic view showing the installation in an automotive vehicle, comprising an internal combustion engine, brake mechanism for the vehicle, and suction or 50 vacuum actuated mechanism for the automotive actuator, and having our present invention embodied therein.

Fig. 2 is an enlarged sectional view of one 55 form of power actuator which may be conveniently employed in an installation of this kind.

Fig. 3 is an enlarged view of certain parts 60 illustrated in Fig. 1, showing the intake manifold and the connection leading from the actuator, and means for carbureting the air withdrawn from the actuator.

Fig. 4 is a partial view of the intake manifold and passage leading from the carburetor thereto, showing a slightly modified 65 form of our invention embodied therein.

Fig. 5 is an enlarged detail view of one form of capillary retaining means which we may employ, and illustrating a preferred means for adjustably supporting a portion 70 therein so that it projects into the intake manifold far enough to intercept a stream of explosive mixture therein.

Fig. 6 is a similar view to Fig. 4, showing another slight modification of our invention.

Fig. 7 represents a detail view of a manifold and carburetor and showing a modified form of our improved means for supplying motor fuel to air exhausted from the suction actuated device, interposed in the pipe or passage connecting the main carburetor with the intake manifold. 75

Fig. 8^a is an enlarged view of a portion of Fig. 8. 85

Fig. 9 is a view similar to Fig. 8, showing a slight modification.

Fig. 9^a is an enlarged sectional view of a portion of Fig. 9. 90

Fig. 10 is a view similar to Fig. 8, showing another slight modification.

Fig. 11 is a partial horizontal sectional view on the line 11—11 of Fig. 10.

Fig. 12 represents, partly in section, one method of applying our invention to a form of intake pipe connecting the main carburetor with the intake manifold, and having a heated portion, heated by the gases of combustion. 95

Fig. 13 is a similar view showing another way in which our invention can be applied to the type of intake passage illustrated in Fig. 12. 100

In Fig. 1, we have shown our invention applied in connection with an automotive vehicle propelled by an internal combustion engine, and having a vacuum or suction operated actuator for operating the brake mechanism of the vehicle. In this figure, 1, represents the cylinder of a power actuator of the kind illustrated, for example, in our former application for Letters Patent of the United States above referred to. The cylinder is provided with a double acting piston, 3, having a hollow piston rod, 5, connected by link, 73, to a brake lever, 72, for operating the form of brake mechanism diagrammatically indicated in Fig. 1, and comprising in this instance a brake band, 71, and brake drum, 70, so that the movement of the piston applies the brakes, and in the opposite direction, releases the brakes. The actuator is provided with suitable reversing valve mechanism, in this instance located in the hub of the piston, and indicated as a whole at 6, the valve mechanism being operated by means of a valve actuating sleeve, indicated at 20, connected by a suitable link with the usual brake operating lever, 74, provided with a retracting spring, 75. As the specific form of valve mechanism 130

has no bearing on our present invention, it will not be described in detail. 26 represents a suction pipe having a flexible portion, which is connected at one end with the valve actuating sleeve, 20, and communicates therewith, and at the other end is connected with the intake manifold, 61, of the internal combustion engine, 60, or in other words, with the suction passage of the engine between the 5 throttle valve, 69, and the cylinder. 66 represents the carburetor, communicating with the manifold by a vertical pipe, 66^a. The valve sleeve, 20, communicates with a suction chamber, 17, in the interior of the piston hub, which can be placed in communication 10 with the cylinder on either side of the piston by means of suitable ports controlled by the reversing valve mechanism. The piston hub is also provided with an inlet chamber, 18, for higher pressure fluid, as atmospheric air, 15 which chamber is in communication through the sleeve, 20, and hollow piston rod, with an inlet aperture, 5^a, formed in the latter. The valve sleeve, 20, is provided with a plug or 20 partition, indicated at 21, separating the air inlet passage to the chamber, 18, from the suction passage to the suction chamber, 17. It will be understood that in the operation of 25 the actuator, a forward movement of the sleeve, 20, in the direction of the arrow in Fig. 2, will admit air into the cylinder in rear of the piston, the forward portion of the cylinder being connected with the intake manifold by the suction pipe, 26, thereby 30 causing the forward movement of the piston, while the movement of the sleeve, 20, in the opposite direction, will reverse the connections with the cylinder, withdrawing the air 35 previously admitted in rear of the piston, from the suction chamber, 17, and suction 40 pipe, 26, and delivering it into the manifold, air at atmospheric pressure being admitted to the cylinder forward of the piston, and thus effecting its return movement. 45

In carrying out our present invention, we interpose between the suction pipe, 26, and the intake manifold of the engine, a capillary retaining means for holding liquid fuel obtained from the manifold, in finely divided 50 condition, and in such manner that the air drawn from the actuator must pass through said capillary retaining means, and in direct contact with the liquid fuel, so as to take up the liquid fuel and form an explosive 55 mixture before the air enters the manifold. We prefer to provide, adjacent to the manifold, a metallic receptacle, 61^a, to which the pipe, 26, is connected, the said receptacle being connected to the manifold by the pipe, 61^b. Within the receptacle, 61^a, which, for 60 convenience of reference, we may designate a trap, we provide the capillary retaining means, which may consist of any suitable material capable of holding liquid hydrocarbon 65 in capillary interstices in the same, or be-

tween portions of the same. For example, we may employ fibrous material, fine wires, asbestos wool, or the like, which will retain the liquid fuel in its interstices and substantially fill the trap, or receptacle, 61^a, so that the air in passing from the pipe, 26, into the manifold, must pass through the capillary retaining means, and in intimate contact with the liquid fuel. We prefer to employ, as a matter of convenience, an absorbent material such as loose wicking, indicated at 61^c, 70 which may be conveniently arranged in coils within the trap or receptacle, 61^a, so as to hold the liquid fuel and force the air to pass through it. The trap may be supplied with liquid fuel by means of the pipe, 61^b, as a certain amount of the liquid fuel taken from the carburetor is deposited upon the walls of the intake manifold, and tends to trickle 75 back toward the entering stream of mixture. A certain amount of it would flow through the pipe, 61^b, into the receptacle, 61^a, and be absorbed by the capillary retaining means 80 therein, when the actuator was not in use. We prefer, however, to provide the receptacle, or trap, 61^a, with an additional pipe, 61^d, connecting it with the manifold, and containing portions of the capillary retaining means, which are projected inwardly into the manifold far enough to be in the stream 85 of explosive mixture passing therethrough, so that portions of the liquid fuel will be caught and retained by the capillary retaining means and conducted into the body of the larger capillary retaining means within 90 the receptacle, 61^a, to insure a supply of liquid fuel therein at all times, in addition to that which may flow into the receptacle, 61^a, through the pipe, 61^b, or independently 95 thereof, as preferred. We prefer to provide 100 the inner end of the pipe, 61^d, within the intake manifold, with fine perforations, as indicated at 61^e, in Figs. 3, and 5, or the upper end of this pipe may be formed of wire 105 gauze, or the upper perforated end of the pipe, 61^d, may be omitted and the capillary 110 retaining medium, if it possesses sufficient stiffness, may be projected beyond the open end of the pipe, 61^d, and into the stream of combustible mixture, to abstract the necessary amounts of liquid fuel therefrom, if preferred. We also prefer to provide means 115 for adjusting the pipe, 61^d, longitudinally so as to cause it to project more or less into the intake manifold, so as to collect more or less 120 of the liquid fuel from the mixture passing therethrough. To this end the pipe, 61^d, may be adjustably connected with the receptacle, 61^a, as by means of the construction illustrated in Fig. 5, and may also be connected 125 in like manner with the intake manifold. For this purpose, we conveniently employ a compression connection, consisting, as shown in Fig. 5, of a collar, 35, externally screw threaded, for engaging a threaded aperture 130

in the part with which it is connected, and provided internally with a tapered portion, indicated at 36, and threaded portions, indicated at 37. In connection with this collar, we use a compressible collar, indicated at 38, having a threaded portion, 39, for engaging the threaded portion, 37, of the collar, and tapered portions terminating in an annular compressible portion, 40, adapted to be forced inwardly when the compression collar, 38, is screwed home, within the collar, 35. The pipe, 61^a, is preferably made of thin brass or other suitable metal and passes through the central openings of the collars, 35 and 38, and when the compression collar, 38, is screwed up tight, the portion, 40, thereof will rigidly clamp and slightly indent the tube or pipe, 61^a, thereby holding it in any position to which it may be adjusted longitudinally, and also compressing the wicking or other capillary retaining material enclosed therein. It will, therefore, be seen that by adjusting the tube, 61^a, inwardly to a greater or less extent with respect to the intake manifold, and also by effecting a greater or less lateral compression of the pipe or tube, 61^a, and the capillary retaining material within the same, the amount of liquid fuel abstracted from the manifold may be adjustably regulated. The receptacle, 61^a, may be provided with a draw-off cock, 61^c, if preferred, so that if an excess of liquid fuel collects in the receptacle, 61^a, it may be drawn off at intervals, or this cock may be utilized in securing the proper adjustment of the tube, 61^a, with respect to the manifold.

In Fig. 4 in which we have shown a slight modification of our invention, 161, represents the manifold, 161^a, the receptacle or trap, 40 connected to the manifold by the pipe, 161^b, and to which the suction pipe, 126, from the actuator is connected. The receptacle or trap, 161^a, is provided with a pipe, 161^d, connecting it with the manifold and extending into the manifold, and provided with perforations, 161^e, the said pipe and the receptacle, 161^a, being filled with the capillary retaining medium, in this instance, the wicking indicated at 161^f, in the manner previously described. In this instance, however, we have provided the lower end of the receptacle, 161^a, with a second pipe, indicated at 161^g, extending through the vertical wall of the passage of the carburetor, and provided within said passage, with perforations, 161^h, said pipe being filled with a continuation of the wicking or other capillary retaining medium. By means of this construction, the capillary material will be supplied with liquid fuel from both of the projecting portions, 161^e and 161^h, of the tubes, 161^d and 161^g, and in case of an excess of liquid fuel being collected within the receptacle, 161^a, beyond the capacity of the capillary retaining material to hold the same, such excess

oil will automatically drain into the vertical passage connecting the manifold with the carburetor, as will be readily seen, so that this construction provides two sources for supplying the capillary retaining material with liquid fuel, and at the same time, a means for automatically preventing an over supply of the same. It will be seen that the air withdrawn from the actuator through the pipe, 126, will be forced to pass through the capillary retaining means, and in intimate relation with the liquid fuel on its way to the carburetor, into which it is discharged through the pipe, 161^b.

In Fig. 6 we have shown another slight modification of our invention in which the capillary retaining medium has a portion extending through the same pipe or passage, by which the receptacle or tube communicates with the intake manifold. In Fig. 6, 261 represents the manifold to which is connected the trap or receptacle, 261^a, by the single pipe or passage, 261^b, and 226 represents the suction pipe from the power actuator or other suction operated device, which is also connected to the receptacle 261^a. Within the receptacle, 261^a, is provided the capillary retaining medium, in this instance, a wicking, 261^c, formed of fine wire, although it may be of any other suitable material, as hereinbefore stated, and we prefer that the wicking should project through the tube, 261^b into the intake manifold, as indicated at 261^d, so as to collect liquid fuel from the stream of charge forming mixture passing from the intake manifold, and also to collect liquid fuel deposited in the adjacent part of the intake manifold, which may flow into the pipe, 261^b, so that the wicking, 261^c, will be supplied with liquid fuel. In this instance we have also shown the receptacle, 261^a, formed in two parts connected in any suitable manner and provided with an inner wall of permeable material, indicated at 262, for example, such inner receptacle may be formed of compressed chamois skin, in a well known manner, and encloses the wicking, 261^c, leaving an air passage, indicated at 263, surrounding the inner permeable wall. The receptacle is also shown with an inwardly extending annular flange indicated at 264, and provided with apertures, 265, therein, for assisting in sustaining the chamois or other permeable wall in position. This inner wall might be formed of wire gauze, or other foraminous material, if desired, and may be held in place in any desired manner. The suction pipe, 226, is connected to the receptacle, 261^a, so that the entering air from the suction actuated device, will be admitted to the space between the inner and outer walls, and will be forced to pass through the permeable inner wall, 262, and through the interstices of the wicking in order to reach the intake manifold. As there is only one pipe connection be-

tween the receptacle, 261^a, and the intake manifold, it is impossible for any air to get into the intake manifold without passing through the capillary retaining medium or wicking, and consequently it will be thoroughly carbureted before reaching the manifold.

In Figs. 7, 8 and 8^a, we have illustrated another form of our invention, in which the means for carbureting the air withdrawn from the vacuum actuated device is in the convenient form of a ring, which can be inserted in the pipe or passage connecting the main carburetor with the intake manifold. In these figures, 361, represents the intake manifold connected to the main carburetor, 366, of any usual or preferred form, by a vertical pipe, preferably formed in two parts, 366^a and 366^b, between which is located a ring, 381, provided with an annular channel, 381, provided with an annular channel, 382, open at the inner face of the ring, exterior to which channel is a second annular channel cored in the ring and indicated at 383, which communicates with the first mentioned channel at intervals by air apertures, 384. The section, 366^a, of the vertical pipe or passage is provided with the usual throttle valve, indicated at 369. The inner face of the ring above and below the annular channel, 382, is provided with grooved portions, indicated at 385, and we prefer to cover the inner face of this ring with a wicking of fibrous absorbent material, usually permeated by air, as for example, a woven fabric of asbestos or other suitable material, indicated at 386. In order to hold this fibrous material in position, and also to prevent any of the particles or loose fibres thereof from passing to the engine, we prefer to place over 40 the fibrous absorbent material, an annular piece of wire gauze, indicated at 387, said gauze and fibrous material being held in position by spring rings, 388, which press the same into the annular grooves, 385. The ring 45 is provided with a nipple, 389, to which the suction pipe, 326, preferably a flexible pipe of rubber or other suitable material, is connected, said nipple communicating with the exterior annular recess, 383, of the ring. This ring, 381, can be readily inserted between 50 the sections of the intake pipe leading to the manifold and secured in position by means of suitable bolts or screws, as indicated at 390, in Fig. 7, passing through lugs or ears, 55 formed on said pipe sections, and the ring, 381, and provided with registering apertures. The annular channel, 382, is preferably provided with a depressed portion, indicated at 391, below the lower lip, 391^a, of the ring, 60 which forms an annular reservoir for the collection and retention of liquid motor fuel, and we prefer to provide the fibrous absorbent material, 386, with capillary tails, indicated at 392, which may be threads drawn 65 out of the material or stitched into the same,

or any other form of capillary appendages may be employed. These tails, 392, have their outer ends extending into the reservoir, 391, formed in the ring.

It will be understood that in this form of our invention, the same operation takes place as that previously described. The absorbent material, 386, will receive and absorb liquid motor fuel from the mixture passing upward from the main carburetor to the manifold, or 70 which may be deposited on the walls of the vertical passage and trickle downward along the walls thereof. Any excess liquid received by the absorbent material will be conducted by the absorbent tails, 392, to and be retained in the reservoir or pocket, 391, formed in the ring, and by means of these absorbent tails, there will be a more or less constant transfer of motor fuel from the said reservoir to the absorbent material, and vice versa, so 75 as to maintain the absorbent material, 386, at all times in a moist condition. When the brake mechanism or other vacuum actuated mechanism is operated so as to withdraw air from the actuator and deliver it into the annular passage, 383, on its way to the manifold, such air will be distributed through the passages, 384, to the channel, 382, of the ring, and will thence pass through the capillary or absorbent material, 386, before it enters 80 the vertical passage connecting the main carburetor to the manifold, which insures the proper mixture of motor fuel with said air, to form a combustible mixture which mixes with the charge forming mixture passing 85 from the carburetor in the manner previously described.

In Figs. 9 and 9^a, we have illustrated a slight modification of the ring shown in Figs. 7, 8 and 8^a. In this construction the ring, 105 indicated at 481, is provided with the inner channel, 482, open to the vertical pipe or passage, the sections of which are indicated at 466^a and 466^b, said ring being provided also with the exterior annular channel, 483, communicating by apertures, 484, with the inner channel, 482. The inner and upper edge of the channel, 482, is carried inwardly to produce an annular flange, 485, which projects 110 into the vertical passages, so as to deflect portions of the charge forming mixture drawn upward from the main carburetor, into the interior channel, 482, to cause it to deposit a portion of its liquid fuel, and said channel, 115 is provided with absorbent material to retain the same, which may be in this instance conveniently provided in the form of a ring, 386, of asbestos or other absorbent material, 120 protected by an exterior coating of wire gauze, 387, and conveniently provided with an interior stiffening wire, 388, said ring being sufficiently flexible to be strung into its place in the channel, 482. The ring is provided with the nipple, 489, connected with the suction pipe, 426, and the operation of 125

the device is practically as that described. It will be seen that the air entering from the suction pipe, 426, will be distributed through the small apertures, 484, into the inner channel, 482, directly in contact with the moist capillary material supported therein. The lower portion of the channel, 482, also forms a reservoir, indicated at 491, the inner lower edge of said channel being provided with an upwardly extending lip, 491^a, as shown.

In Figs. 10 and 11 we have shown another slight modification of the ring and the capillary material carried thereby. In this instance the sections of the vertical passage are indicated at 566^a and 566^b, and the ring itself is indicated at 581, being conveniently formed in two sections for convenience of manufacture. 582 represents the inner channel, and 583, the exterior channel, communicating with the inner channel by apertures, 584, which are located adjacent to the bottom of the channel, 582, and said channel is provided with a lip, 591^a, at its lower edge, forming a liquid reservoir, 591, and with a downwardly extending lip, 585, at its upper edge. Within the channel is provided an annular ring, 586, of capillary material, such as an absorbent mass of fibrous material pressed into form, for example, asbestos, and which may be protected by a covering of wire gauze or other material as desired, the said ring being provided on its inner edge with radially disposed projections, or tongues, 586^a, which project over the lip, 591^a, toward the interior 35 of the vertical passage from the main carburetor. In this instance the inwardly projecting tongues, or fingers, 586^a, thus serve to collect liquid motor fuel from the charge forming mixture passing upwardly from the 40 main carburetor, and by capillary action, transmitted to the main body of the ring, 586, and to the reservoir, 591, in the manner hereinbefore described, the said ring being provided with depending portions, 586^b, or 45 capillary tails to insure the transfer of liquid to and through said reservoir. The air entering from the suction actuated device through the pipe, 526, passes through the small apertures, 584, into said reservoir, 591, 50 and through the absorbent material of the ring, 586, becoming admixed with motor fuel and entering the passage, as explosive mixture to be mixed with the charge forming mixture, as hereinbefore described.

55 In some of the carburetors now in use the passage connecting the main carburetor with the intake manifold is provided with a pocket having heating means of some kind into which the mixture is deflected for the purpose of 60 more perfectly vaporizing the liquid motor fuel and insuring a dry mixture reaching the cylinders from the engine. Our invention is equally applicable to this type of carburetor and we have shown in Figs. 12 and 13, two 65 forms in which our invention may be per-

fectly applied thereto. Referring to Fig. 12, 661, represents the intake manifold connected to the main carburetor by the vertical passage, 666^b, which is provided with a pocket or recess, 666^c, having a heating jacket, 666^d, through which heated products of combustion are passed, the said passage being also provided with a deflector, 666^e, for deflecting the charge forming mixture into said heating pocket. In this instance we have shown a mass of fibrous capillary material indicated at 686, preferably surrounded by a protecting layer of wire gauze, 687, and located in the bottom of the heating pocket, 666^c, and connected with the suction pipe, 626, which is passed through the heating jacket and discharges the air withdrawn from the suction actuated device through the absorbent material, 686. This absorbent or capillary material will take up a certain amount of the liquid fuel from the mixture and give it off to the air admitted through the vacuum or suction pipe, 626, before permitting it to pass into the passage, 666^b, on its way to the manifold and the operation of the device is substantially as before described.

In Fig. 13, the manifold is indicated at 761, the heating pocket, 766^c, the passage at 766^b and the heating jacket for the heating pocket is indicated at 766^d. In this instance we have shown a mass of capillary or fibrous absorbent material at 786, protected by a covering of wire gauze, 787, and supported at the other side of the pocket and connected with the suction pipe, 726, leading from the vacuum actuated device and passing through the heating jacket, 766^d. The operation of the device is exactly the same as that previously described.

It will be understood that in all of the forms of our invention, we prefer to connect the suction pipe to the suction passage of the engine between the throttle valve and the cylinders.

The specific forms of our invention illustrated in Figs. 7, 8, 8^a, 9, 9^a, 10 and 11 are not specifically claimed herein, as they form the subject matter of a divisional application for Letters Patent of the United States filed September 18, 1926 and given Serial No. 136,226.

While we have herein shown the actuator connected with brake mechanism of an automotive vehicle, it is obvious that it might be employed to operate other devices which are intermittently operated, as for example, the door mechanisms of busses and other vehicles, which are also intermittently operated.

What we claim and desire to secure by Letters Patent is:—

1. The combination with an internal combustion engine, provided with a suction passage communicating with the engine cylinder, or cylinders, a carburetor connected thereto for supplying the normal charges for the

- engine cylinders at all speeds, a throttle valve for controlling said passage, a suction actuated device, and a suction pipe connecting it with said passage, of a receptacle 5 interposed between said suction pipe and the said suction passage, and a capillary medium within said receptacle for holding said liquid fuel collected from said suction passage, and effecting the carburetion of the air with- 10 drawn from the suction actuated device before it reaches the suction passage to prevent interference with the operation of the engine or stalling it if idling, by the operation of the suction actuated device, said capillary medium having portions projecting from the upper end of said receptacle into a portion of 15 said suction passage adjacent to the engine cylinder, or cylinders, and a portion projecting from the lower end of said receptacle into a vertically disposed portion of said suction passage, adjacent to the carburetor, for collecting liquid fuel from the charge forming mixture and automatically draining said receptacle of excess liquid fuel so collected 20 thereby in excess of its ability to hold the same.
2. The combination with an internal combustion engine provided with an intake manifold having a passage leading to the carburetor, a carburetor operatively connected with said passage for supplying the normal charges for the engine cylinders at all speeds, a throttle valve for said passage, and a suction operated device, of a receptacle having 25 an air connection with the manifold extending from the said receptacle and projecting into said manifold, and provided with perforated portions within the manifold in the path of the normal charges passing there- 30 through, a capillary retaining medium within said receptacle having portions extending through said collecting pipe into the manifold, and a suction pipe connecting said receptacle with the suction operated device.
3. The combination with an internal combustion engine provided with an intake manifold having a passage leading to the carburetor, a carburetor operatively connected with said passage for supplying the normal 35 charges for the engine cylinders at all speeds, a throttle valve for said passage, and a suction operated device, of a receptacle having an air connection with the manifold and ex- 40 tends from the said receptacle and projecting into said manifold, and provided with perforated portions in the path of the normal charges passing therethrough and a liquid collecting and draining pipe extending from the lower portion of said receptacle into the 45 vertical passage connecting the carburetor with the manifold and projecting into said passage and provided with perforated portions therein in the path of the normal charges passing therethrough, a capillary re- 50 taining medium within said receptacle having 55 portions extending through said liquid collecting pipes into said manifold within the perforated portions of said pipes, and vertical passage respectively, and a suction pipe connecting said receptacle with the suction 60 actuated device.
4. The combination with an internal combustion engine provided with a suction passage communicating with the engine cylinder or cylinders, and with a carburetor, for supplying the normal explosive charges to the engine at all speeds, and a throttle valve for controlling said passage, an intermittently operated suction actuated device, and a suction pipe connecting the suction actuated device and said suction passage between the throttle valve and the engine cylinder, or cylinders, of a capillary medium for collecting liquid fuel from the normal charge forming mixture passing through said suction passage, and means for passing the air withdrawn from the suction actuated device in intimate relation to said capillary retaining medium and the liquid fuel held thereby to fuelize said air before it enters said suction 70 passage, and prevent interference with the operation of the engine and stalling it if idling, by the operation of the suction actuated device.
5. The combination with an internal combustion engine provided with a suction passage communicating with the engine cylinder or cylinders, and with a carburetor, for supplying the normal explosive charges to the engine at all speeds, and a throttle valve for controlling said passage, an intermittently operated suction actuated device, and a suction pipe connecting the suction actuated device and said suction passage between the throttle valve and the engine cylinder, or cylinders, of means for collecting excess liquid fuel from the normal charge forming mixture passing through said suction passage, interposed in the suction connection between the suction actuated device and the suction passage, to fuelize the air withdrawn from the suction actuated device before it enters the suction passage, and preventing interference with the operation of the engine and stalling it if idling, by the operation of the suction actuated device, and means for automatically returning excess liquid fuel so collected beyond the capacity of the collecting means, to the stream of normal charge forming mixture passing through said suction 80 passage.
6. The combination with an internal combustion engine, provided with a suction passage communicating with the engine cylinder or cylinders, a carburetor connected thereto, for supplying the normal charges to the engine at all speeds, a throttle valve for controlling said passage, a suction actuated device comprising a cylinder and a piston connected to a part to be intermittently operated, and a 85

suction pipe connecting it with said passage, of a receptacle interposed between said suction pipe and the said suction passage, and a capillary medium in the path of the air withdrawn 5 from the suction actuated device located within said receptacle, for holding liquid fuel collected from said suction passage, to fuelize said air before it reaches the suction passage, to prevent interference with the operation of 10 the engine or stalling it if idling, by the operation of the suction actuated device, said capillary medium having portions extending into said suction passage and projecting into the stream of charge forming mixture passing therethrough, to facilitate the collection of liquid fuel from said suction passage.

7. The combination with an internal combustion engine provided with a suction passage communicating with the engine cylinder 20 or cylinders, a carburetor connected thereto, for supplying the normal charges to the engine at all speeds, a throttle valve for controlling said passage, a suction actuated device comprising a cylinder and a piston connected to a part to be intermittently operated, and a suction pipe connecting it with said passage, of a receptacle interposed between said suction pipe and the said suction passage, and a capillary medium in the path of 25 the air withdrawn from the suction actuated device located within said receptacle, for holding liquid fuel collected from said suction passage, to fuelize said air before it reaches the suction passage, to prevent interference with the operation of the engine or 30 stalling it if idling, by the operation of the suction actuated device, said capillary medium having portions extending into said suction passage and projecting into the stream of charge forming mixture passing therethrough, to facilitate the collection of liquid fuel from said suction passage, and means for adjusting the extent to which said capillary medium projects into said suction 35 passage to regulate the collection of liquid fuel therefrom.

8. In brake mechanism for automotive vehicles provided with an internal combustion engine having a suction passage communicating with the engine cylinder or cylinders, and a carburetor connected therewith for supplying the normal charges to the engine at all speeds, and a throttle valve for controlling said passages, the combination 50 with a suction actuated device comprising a cylinder and a piston therein operatively connected with brake mechanism of the vehicle, a suction pipe for connecting the suction actuated device with said suction passage, and controlling valve mechanism for the suction actuated device, of a receptacle interposed between said suction pipe and the said suction passage, and a capillary medium in the path of the air intermittently withdrawn 55 from the suction actuated device

located within said receptacle for holding liquid fuel collected from said suction passage to fuelize said air before it reaches the suction passage to prevent interference with the operation of the engine or stalling it if 70 idling by the operation of the suction actuated device, said capillary medium having portions extending into said suction passage and projecting into the stream of normal charge forming mixture passing therethrough, to facilitate the collection of liquid fuel from said suction passage.

9. In brake mechanism for automotive vehicles provided with an internal combustion engine having a suction passage communicating with the engine cylinder or cylinders, and a carburetor connected therewith for supplying the normal charges to the engine at all speeds, and a throttle valve for controlling said passages, the combination 80 with a suction actuated device comprising a cylinder and a piston therein operatively connected with brake mechanism of the vehicle, a suction pipe for connecting the suction actuated device with said suction passage, and controlling valve mechanism for the suction actuated device, of a receptacle interposed between said suction pipe and the said suction passage, and a capillary medium in the path of the air intermittently withdrawn 85 from the suction actuated device located within said receptacle for holding liquid fuel collected from said suction passage to fuelize said air before it reaches the suction passage to prevent interference with the operation of the engine or stalling it if idling by the operation of the suction actuated device, said capillary medium having portions extending into said suction passage and projecting into the stream of normal charge forming mixture passing therethrough, to facilitate the collection of liquid fuel from said suction passage, and means for adjusting the extent to which said capillary medium projects into said suction passage to regulate the collection of liquid fuel therefrom.

10. The method of operating a suction actuated device deriving its suction from an internal combustion engine, which consists in withdrawing excess liquid fuel from the normal explosive charges delivered to said engine and conveying said excess liquid fuel by capillary action into the path of air withdrawn from the suction actuated device, to carburet said air, and then combine it with the normal explosive charges to prevent stalling or otherwise interfering with the operation of the engine when the suction actuated device is operated.

11. The method of operating a suction actuated device deriving its suction from an internal combustion engine, which consists in withdrawing excess liquid fuel from the normal explosive charges delivered to said

- engine, conveying said excess liquid fuel by a capillary action into the path of the air withdrawn from the suction actuated device, to carburet said air, and combine the same with the normal explosive charges to prevent 5 stalling or otherwise interfering with the operation of the engine when the suction actuated device is operated, and returning all excess fuel unvaporized by air from the actuator into the normal charge forming mixture.
- 10 12. The method of operating a suction actuated device deriving its suction from an internal combustion engine, which consists in removing from the normal explosive charges excess liquid fuel, presenting said excess 15 liquid fuel to the action of the air withdrawn from the suction actuated device to carburet said air, and then combining said carbureted air with the normal explosive charges to prevent interference with the engine when the 20 suction actuated device is operated.

In testimony whereof we affix our signatures.
